UNITED STATES PATENT OFFICE.

ROBERT R. WADDELL, OF HILLSBOROUGH, OHIO.

POCKET-RULE.

SPECIFICATION forming part of Letters Patent No. 358,308, dated February 22, 1887.

Application filed August 23, 1886. Serial No. 211,632. (No model.)

To all whom it may concern:

Be it known that I, ROBERT R. WADDELL, of Hillsborough, county of Highland, State of Ohio, have invented a new and useful Improvement 5 in Measuring-Rules, of which the following is a full, clear, and exact description, reference being had to the accompanying drawings, making part of this specification.

My invention relates to carpenters' measuring-rules; and it is particularly applicable to the pocket or folding type of this and other similar kinds of measuring-rules.

The object of my invention is to provide an attachment for such measuring-rules, whereby 15 an angle of any given number of degrees may be readily found without employing mathematical calculation or geometrical drawing, thus greatly facilitating and simplifying the operation.

20 To the above purpose my invention consists in a graduated arm pivoted upon the measuring-rule, and adapted to be extended therefrom so as to conform to a circular line of movement described by said rule, as herein-after described and claimed.

25 My invention further consists in certain peculiar and novel features of construction and arrangement, as hereinafter described and claimed.

30 In order that my invention may be fully understood, I will proceed to describe it with reference to the accompanying drawings, in which—

Figure 1 is a plan view of a measuring-rule 35 in folded condition with my improved attachment applied thereto. Fig. 2 is a similar view showing the attachment extended. Fig. 3 is a plan view of the rule and its attachment, both extended as in use.

40 In the said drawings, *a* designates a pocket-rule having the middle pivot-joint, *a'*, and the two hinge-joints *a²* *a³* in the usual manner. Upon one of the outer arms, *a⁴*, of the said rule is formed a recess, *a⁵*, which extends parallel with one edge of said arm, and has at one end an enlargement, *a⁶*.

Within the recess *a⁵* is placed the attachment *B*, which is a straight arm corresponding in form and dimensions with the recess *a⁵*,

and having at one end an enlargement, *b*, fitting the enlargement *a⁶* of recess *a⁵* and pivoted therein, as shown at *b'*. Upon one of its sides this arm *B* is graduated to fractions of inches, as at *b²*, so that when the arm is not extended its outer graduated side shall conform to the graduations upon the rule. Upon the opposite or under side the said arm is graduated to degrees of a circle, whose center is the pivot *a'*, and whose radius is a line drawn from the pivot-joint *a'* to the pivot *b'* of the 55 arm *B*.

In order to find the degree of an angle, the rule *a* is extended, as shown in Fig. 3, and the arm *B* is extended out of its recess *a⁵*, so as to lie at right angles to the contiguous edge 65 of the rule. The pivot of joint *a'* is placed upon the vertex of the angle, and the arm *a⁷* of the rule is held firmly in stationary condition while the arm *a⁴* is moved in the arc of a circle equal in length to the arm *B*. The 70 lower edge of the rule will now be on an angle of fifteen degrees from the point started from. This circular movement being continued, any desired number of degrees of a circle may be readily reached and quickly indicated upon 75 the surface being measured. A single degree is indicated by dotting a line at the one-degree mark of arm *B*, and continuing the movement of arm *a⁴* as before till the point is on a line with the dot, when the angle will measure 80 exactly one degree.

The attachment may be of metal or other suitable material, and does not interfere with the ordinary uses of the rule, while greatly extending the usefulness of the latter. 85

Having thus described my invention, what I claim as new, and desire to secure by Letters Patent, is—

1. The combination, with a measuring-rule, of an arm graduated upon one side to fractions 90 of inches and upon the opposite side to degrees of a circle, and pivoted upon one arm of the rule, substantially as described.

2. The combination, with a measuring-rule having a recess, *a⁵*, with an enlarged portion, 95 *a⁶*, said recess being formed in the edge of one arm of the rule, of an arm, *B*, graduated upon one side to fractions of inches and upon the

opposite side to fractions of degrees, and pivoted in said recess, one end of said arm B being enlarged to fit the enlarged portion of the recess, as set forth.

5 3. The rule a , having joints $a' a'' a'''$, and arms $a^4 a^7$, and provided with the recess a^5 , with its enlargement a^6 , in combination with the arm B, having enlargement b and pivot b' , and

graduated sides $b^2 b^3$, substantially as and for the purpose specified.

In testimony whereof I have hereunto set my hand this 30th day of June, A. D. 1886.

ROBERT R. WADDELL.
